UNITED STATES PATENT OFFICE.

EDWARD J. BROOKS, OF EAST ORANGE, NEW JERSEY, ASSIGNOR TO
E. J. BROOKS & COMPANY, OF NEW YORK, N. Y.

POST-OFFICE HAND-STAMP.

SPECIFICATION forming part of Letters Patent No. 451,887, dated May 5, 1891.

Application filed February 9, 1891. Serial No. 380,745. (No model.)

To all whom it may concern:

Be it known that I, EDWARD J. BROOKS, a citizen of the United States, and a resident of East Orange, in the State of New Jersey, 5 have invented a new and useful Improvement in Post-Office Hand-Stamps, of which the following is a specification.

This invention relates to improvements in the hand-stamps now in use by the Post-Office 10 Department for canceling postage-stamps and postmarking mail, and primarily to those stamps which combine stamp-canceling and postmarking or dating devices, hereinafter termed, respectively, the "canceler" and the 15 "dater."

The invention consists in certain novel combinations of parts or features of construction, hereinafter set forth and claimed, and in an improved double stamp embodying 20 the same; and its objects are, first, to provide the dater with its permanent lettering for the individual post-office, or a portion thereof, in such a manner as to insure at once superior lettering and equal or reduced cost; secondly, 25 to adapt the canceler to be made with a molded face on a durable elastic body, so as to insure distinct and ineffaceable canceling impressions, and, thirdly, to combine such advantages in a simple and durable double 30 stamp.

A sheet of drawings accompanies this specification as part thereof.

Figure 1 of the drawings is a perspective view of an improved double stamp illustrating this invention. Fig. 1^x is a perspective view of a part thereof detached. Fig. 2 represents a longitudinal section of the same. Fig. 3 represents a section on the line 3-3, Fig. 2. Fig. 4 is an end view of the head or body portion of an improved double stamp of a different pattern. Fig. 5 represents a longitudinal section of an improved dater embodied in a single stamp. Fig. 5^x represents two magnified fragmentary sections illustrating 45 an alternative detail. Fig. 6 represents a longitudinal section of the face end of a modified dater. Figs. 7 and 8 are face views of double and single stamps of another pattern embodying the same invention, in part; and 50 Fig. 9 represents a longitudinal section of the last-named single stamp, Fig. 8.

Like letters of reference indicate corresponding parts in the several figures.

The improved double hand-stamp represented by Figs. 1 to 3, inclusive, is composed 55 of a central wooden handle A, a steel cross-bar B, having a tang b, Fig. 2, by which the handle is attached, a dater C, the body of which is integral with one end of said cross-bar, a canceler D, attached to the other end 60 of the cross-bar B, and a screw E, Fig. 2, inserted from the back of the cross-bar B into the upper end of the brass shell of said canceler D, to so attach the latter. Said permanent lettering of the dater C, being in 65 the example "Phila., Pa.," for Philadelphia, Pennsylvania, is engraved or produced in any approved way upon a separate steel ring c, (shown detached by Fig. 1^x), and is thus adapted to be of a better quality than 70 heretofore with finer and deeper letters, and at the same time as cheap as, if not cheaper than, the customary lettering "engraved" on the body of the dater. The ring c is fitted to an annular recess c² in the face 75 end of the body of the dater, as shown in Fig. 2, and may be riveted or otherwise fastened in place in any approved manner. Rivets r, parallel with the face of the dater, are represented by dotted lines in Fig. 3. Instead 80 of thus using one or more separate rivets for holding the ring c in place, I propose to provide the face of the dater with a thin annular projection p, Fig. 5^x, that can be "matted" down over the inner edge of the ring so as to 85 fasten the latter, as represented at m in the lower sectional view. The one-part body of the dater is constructed with the customary central recess c³, which is rectangular or substantially rectangular in cross-section, as 90 shown in Figs. 1 and 3.

In order to provide a smooth, true, and durable abutment c⁴ for the heel ends of the changeable type t to rest upon, I undercut the inner or upper end of said recess c³, as represented in Figs. 2 and 3, and at the same time finish the entire area of said abutment by a milling operation that is readily performed and does not materially add to the cost of manufacture. Said abutment thus 95 formed is composed of the solid steel of the body of the dater, and is consequently free 100

from liability to become uneven by wear. A thumb-screw s provides, by way of illustration, for fastening the changeable type in place in an approved way. The customary 5 marginal projection c^5 on the face of the dater for printing the border of the postmark is preferably formed on the body of the dater, as heretofore. The shell of the canceler D is preferably made of brass, as above, and is 10 in the form of a cylindrical cup, the face of this particular canceler being round, having a central screw-hole d in its upper or closed end communicating with the interior of the shell and an internal anchoring-groove d^2 15 parallel with the open end of the shell. To complete the canceler, said shell is placed with its open end downward into a suitable mold having upon its upturned bottom a sunken counterpart of the desired canceling 20 impression and liquid roller-composition— such as is used in making printers' inking-rolls or preferably a mixture of the same—or of any suitable gelatine compound with cork-dust is poured through the screw-hole d into 25 the interior of the shell and its said anchoring-groove d^2 and upon the bottom of the mold, so as to make the remainder of the canceler of such elastic composition or mixture and especially its protruding portion and 30 face, the latter being thus readily and cheaply molded and provided with any desired design or figure. The elastic composition or mixture is readily cut out of the screw-hole d , and the completed canceler D is then attached to the cross-bar B by the screw E, as 35 in the drawings.

In the modification illustrated by Fig. 4 the canceler D is of the prescribed alternative oval shape in cross-section. Otherwise 40 the modified stamp is substantially identical with the double stamp already described.

The lettering-ring c , as well as the changeable type t of the dater, and the elastic filling of the canceler are omitted in the figure, so 45 as to show more clearly the annular recess c^2 and central recess c^3 of the dater and the cup of the canceler.

In the modification illustrated by Fig. 5 the improved dater C, as shown in Figs. 1 to 50 3 and Fig. 4, as above, is simply embodied in a single hand-stamp—that is to say, the cross-bar B is omitted and the handle-tang b is integral with the steel body of the dater.

The lettering-ring c of each of the stamps 55 above described is intended to be made of steel, either endless, as shown, or of one or more pieces bent into shape from a straight bar, as illustrated by the dotted joint line at j in Fig. 4^x. In the form last described the

lettered bar may be produced in the most 60 rapid and inexpensive way by means of die-rolls. Otherwise the ring is intended to be swaged and lettered by means of suitable dies.

In the modification illustrated by Fig. 6 65 the annular recess c^2 is cut deeper and provided with lateral anchoring-grooves c^6 , and the lettering-ring c is cut within said recess and grooves, and within a suitable molding-die, of type-metal or any suitable alloy. The 70 cost of manufacture may thus be still more greatly reduced.

In the modifications illustrated by Figs. 7, 8, and 9 the separate lettering-ring c is used alone in hand-stamps which are otherwise of 75 an ordinary construction. Apart from said separate ring c these hand-stamps form no part of my invention, and need not therefore be more particularly described.

Other like modifications will suggest themselves to those skilled in the art, and details which have not been specified may be of any approved description.

Having thus described the said improvement, I claim as my invention and desire to 80 patent under this specification—

1. In a post-office hand-stamp, a dater having its permanent lettering or a portion thereof on a separate ring immovably fastened within an annular recess in the face end of 90 the body of the dater, substantially as hereinbefore specified.

2. In a post-office hand-stamp, a canceler composed of a cup-shaped metallic shell provided with a screw-hole in its closed end and 95 with an internal anchoring-groove, and an elastic inner and face portion of roller-composition or the like, cast fast within said shell, substantially as hereinbefore specified.

3. An improved post-office hand-stamp 100 composed of a central non-metallic handle, a cross-bar of steel provided with the handle-tang, a dater the body of which is integral with one end of said cross-bar and is provided with a separate ring bearing the permanent lettering or a portion thereof and with changeable dating-type and a fastening therefor, a canceler composed of a cup-shaped metallic shell and an elastic inner and face portion of roller-composition or the like, and 105 a screw attaching said canceler to the other end of said cross-bar, substantially as hereinbefore specified.

EDWARD J. BROOKS.

Correction in Letters Patent No. 451,887.

It is hereby certified that in Letters Patent No. 451,887, granted May 5, 1891, upon the application of Edward J. Brooks, of East Orange, New Jersey, for an improvement in "Post-Office Hand Stamps," an error appears requiring the following correction: In line 68, page 2, of the printed specification, the word "cut" should read *cast* and that the Letters Patent should be read with this correction therein to make the same conform to the record of the case in the Patent Office.

Signed, countersigned, and sealed this 12th day of May, A. D. 1891.

[SEAL.]

CYRUS BUSSEY,
Assistant Secretary of the Interior

Countersigned:

C. E. MITCHELL,
Commissioner of Patents.
